CLAIM

The ornamental design for a battery, as shown and described.

DESCRIPTION

FIG. 1 is a front perspective view of a battery showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear perspective view thereof.

The dashed broken lines in the figures represent portions of the battery that form no part of the claimed design.

The dot-dash broken lines in the figures represent a boundary line that forms no part of the claimed design.

1 Claim, 6 Drawing Sheets(56)
